(57) **CLAIM**

The ornamental design for a soap-dish and holder assembly, as shown and described.

DESCRIPTION

FIG. 1 is a top, front, left-side perspective view of a soap-dish and holder assembly showing my new design;

FIG. 2 is a top plan view thereof;

FIG. 3 is a left side elevational view thereof;

FIG. 4 is a bottom plan view thereof;

FIG. 5 is a left side elevational view thereof, the right side elevational view being mirror symmetrical thereto;

FIG. 6 is a rear view thereof; and,

FIG. 7 is a front elevational view thereof.
